WALL SURFACE BATH FAUCET FITTING

Walter Baker, Jr., Louisville, Ky., assignor to
American Radiator & Standard Sanitary Cor-
poration, Pittsburgh, Pa., a corporation of
Delaware

Application April 1, 1953, Serial No. 24,287

Term of patent 14 years

(Cl. D91—3)

To all whom it may concern:

Be it known that I, Walter Baker, Jr., a citizen
of the United States, residing at Louisville,
State of Kentucky, have invented a new, original,
and ornamental Design for a Wall Surface Bath
Faucet Fitting, of which the following is a speci-
fication, reference being had to the accompany-
ing drawing, forming a part hereof.

Figure 1 is a front perspective view of a wall
surface bath faucet fitting embodying my new
design;

Figure 2 is a top plan view thereof on a re-
duced scale; and

Figure 3 is a front elevation thereof on a re-
duced scale.

I claim:
The ornamental design for a wall surface bath
faucet fitting, substantially as shown.

WALTER BAKER, JR.
